ARTHUR SIMON, OF MILWAUKEE, WISCONSIN, ASSIGNOR TO THE CUTLER-HAMMER MFG. CO., OF MILWAUKEE, WISCONSIN, A CORPORATION OF WISCONSIN.

CONTROLLER FOR ALTERNATING-CURRENT MOTORS.

1,413,544.

Specification of Letters Patent. Patented Apr. 18, 1922.

Application filed December 26, 1919. Serial No. 347,253.

To all whom it may concern:

Be it known that I, ARTHUR SIMON, a citizen of the United States, residing at Milwaukee, in the county of Milwaukee and 5 State of Wisconsin, have invented new and useful Improvements in Controllers for Alternating-Current Motors, of which the following is a full, clear, concise, and exact description, reference being had to the accompanying drawing, forming a part of this specification.

This invention relates to controllers for alternating current motors and other power consuming devices having mutual inductance.

It has been proposed to control three phase devices of such character by means of V or open delta connected three phase transformers, but the latter, as heretofore constructed, 20 inherently tend to produce phase distortion resulting, when used for motor control, in very serious reduction of the motor torque particularly during starting under heavy load.

25 The present invention has among its objects that of overcoming such tendency of transformers of the character stated.

Another object is that of providing a controller for use in the foregoing relation, including a three phase V-connected transformer wherein provision is made for maintaining for the energy transmitted thereby, substantially the phase balance of the supply line.

35 Another object is to provide an improved core member for transformers of the aforesaid and other types.

Other objects and advantages will herein-after appear.

40 In the accompanying drawing, Figure 1 is a front elevational view of a transformer illustrative of the invention, also illustrating diagrammatically certain proposed circuit connections therefor; while,

45 Fig. 2 is a horizontal sectional view of the same, the coils and circuit connections being omitted.

50 Referring to Fig. 1 of the drawing, the same illustrates a three phase auto-transformer connected in V or open delta to supply lines A, B, C and adapted to transmit electrical energy therefrom to a motor M which may in practice be of the squirrel cage or other preferred type.

55 Said transformer includes a magnetic

frame or core member 5 having parallel legs 6, 7 and 8 terminally connected by transverse upper and lower portions 9 and 10, the outer legs 6 and 8 being provided with coils 11 and 12 respectively and the center leg 7 60 being un-wound.

A transformer frame so constructed and connected is traversed during different portions of the cycle by varying fluxes, the chief of which are indicated by force lines 13, 14 65 and 15, said fluxes being moreover partially concurrent or overlapping one another in point of time. Thus the center leg during part of the cycle is traversed by a material portion of the flux of both of the outer legs, 70 the theoretical value of the effective flux in said center leg being equal to the product of the flux in either outer leg times the square root of three. Hence in designing transformers of this type it has been customary 75 to make the cross area of the center leg bear a substantially corresponding relation to the cross area of the outer legs, thereby providing for a substantially uniform flux density in the several legs.

It has, however, been determined practically that the regulation effected by the transformer is greatly improved by making the cross area of said center leg considerably less than that theoretically required, thus 85 effecting a relatively high magnetic saturation of said center leg and consequent increase in impedance of those components of the electromagnetic circuit of the transformer which include the center leg, relative to the impedance of those components including only the outer legs. The proportion of the total flux carried by said center leg is thus reduced, with a corresponding relative increase in mutual inductance of the coils 90 of the outer legs, which condition is highly favorable to the phase stabilizing tendency inherent in the windings of the motor.

95 In both figures of the drawing the dotted lines associated with the center leg 7 indicate approximately the lateral extent of said member theoretically required to give a uniform density of the effective flux in the several legs, while the full lines indicate the reduced dimension of said member calculated to provide the accentuated flux density contemplated herein.

100 By thus proportioning the cross areas and consequent flux densities of the center to the outer legs, it has been found possible to 110

render the operative characteristics of this type of transformer the same, as regards torque of the supplied motor, as those exhibited by transformers of like capacity 5 having symmetrically arranged coils.

Considering the structure of the core member more in detail, the upper and lower transverse portions 9 and 10 are formed integral with the center leg 7 while the outer 10 legs 6 and 8 are of unreticulated form and hence adapted to ready assembly of the coils thereon. Said outer legs are moreover of suitable length for clamping respectively against the oppositely projecting ends of 15 said transverse portions 9 and 10, all of said sections being composed of suitably insulated laminae.

Upper and lower clamping devices 16 and 17 serve for securement of the various core 20 sections in assembled relation and also for mounting of the assembled transformer upon a suitable support 18.

Referring particularly to Fig. 2, each of said clamping devices comprises a pair of 25 relatively rigid metallic strips or bars 19 and 20 extending longitudinally of the core member and having its terminal portions up-bent and punched to provide lugs 21 and 22, and a pair of relatively short transverse 30 bars 23 and 24 similarly provided with lugs adapted to be secured to the corresponding lugs of the bars 19 and 20 by means of bolts 25. In practice the several bars may 35 preferably be of such relative lengths and contour as to render the various pairs of co-operating lugs slightly divergent from their outer ends inwardly, whereby upon tightening the bolts 25 a strong clamping action is effected both for forcing and holding the 40 outer core sections against the end portions of the central section and also for maintaining the respective upper and lower portions of the laminae in suitable contact. The central portions of the laminae may be 45 clamped in suitable contact by means of rivets 26 extending transversely through the respective core sections, or otherwise.

Each of the lugs 21 of the upper and lower elongated clamping bars 19 is further 50 more extended to provide terminally located feet 27 for mounting of the transformer upon the support 18.

Although the circuit connections illustrated are those of an auto-transformer it is 55 to be understood that all of the foregoing features are equally applicable to pure induction transformers.

What I claim as new and desire to secure by Letter's Patent is:

60 1. In an alternating current controller, the combination with a power consuming device whose operation is characterized by mutual inductance, of a transformer to supply electrical energy thereto, said transformer comprising a magnetic frame hav-

ing spaced legs and an intermediate leg, said spaced legs carrying respectively V-connected coils adapted to mutually inductive action and said intermediate leg being proportioned with reference to said spaced legs 70 to increase the mutual inductance of said coils.

2. In an alternating current controller, the combination with a power consuming device having an inherent tendency against phase distortion of its circuit, of an energy supplying transformer comprising a pair of coils connected in open delta to a three phase supply circuit and a magnetic frame having spaced legs carrying said coils respectively 80 in a relation of mutual inductance and an intermediate leg adapted to carry a portion of the flux induced by each of said coils, said legs being relatively proportioned to accentuate the mutual inductance of said coils for supporting such tendency of said power consuming device. 85

3. In an alternating current controller, the combination with a power consuming device having an inherent tendency against phase distortion of its circuit, of an energy supplying transformer comprising a pair of coils connected in open delta to a three phase supply circuit and a magnetic frame having spaced legs carrying said coils respectively 90 in a relation of mutual inductance and an intermediate leg adapted to carry a portion of the flux induced by each of said coils, the cross area of said intermediate leg being so related to the cross areas of said spaced legs as to 95 reduce the proportion of the total effective flux carried by the former for supporting such tendency of said power consuming device.

4. A three phase alternating current transformer comprising a magnetic frame having a center leg and a pair of outer legs, and open delta connected coils carried by said outer legs respectively, said center leg and said outer legs being proportioned to ac- 100 centuate the flux density of the former. 105

5. A three phase alternating current transformer comprising a magnetic frame having a center leg and a pair of outer legs, and open delta connected coils carried by said outer legs respectively, said center leg and said outer legs being proportioned to accentuate the mutual inductance of said coils. 115

6. A three phase alternating current transformer comprising a magnetic frame having a center leg and a pair of outer legs, and open delta connected coils carried by said outer legs respectively, said center leg and said outer legs being proportioned to render the flux density of the former higher than 120 that of the latter for accentuating the mutual inductance of said coils. 125

7. A three phase alternating current transformer comprising a magnetic frame having three associated legs, two of said legs having 130

electromagnetic coils connected in open delta and the third leg being arranged to carry a portion of the flux induced by said coils, the cross areas of said legs being proportioned 5 to increase the flux density of said third leg for decreasing the proportion of the total effective flux carried thereby.

8. An alternating current transformer comprising a frame having three magnetically connected legs, a pair of electromagnetic coils connected in open delta to a three phase supply circuit associated with the legs of said frame to cause two of said legs to act in a relation of mutual inductance and 10 the third leg to carry a portion of the flux induced by each of said coils, said third leg being so proportioned with respect to said other legs as to increase the impedance of 15

those components of the electromagnetic circuit of the transformer which include the 20 center leg, relative to the impedance of the components including only the outer legs.

9. A three phase alternating current transformer comprising a magnetic frame having a pair of spaced coil-carrying legs and an 25 intermediate leg, the coils of said spaced legs being connected in open delta and the cross area of said intermediate leg being greater than that of either of said spaced legs, but less than the product of the cross 30 area of either of said spaced legs times the square root of three.

In witness whereof, I have hereunto subscribed my name.

ARTHUR SIMON.
